Patented Nov. 2, 1915.

UNITED STATES PATENT OFFICE.

CHARLES E. GREEN AND CHARLES T. BLOOMER, OF NEWARK, NEW YORK.

CORNER CONSTRUCTION FOR BOXES.

1,158,801.

Specification of Letters Patent.

Patented Nov. 2, 1915.

Application filed March 3, 1915. Serial No. 11,761.

To all whom it may concern:

Be it known that we, CHARLES E. GREEN and CHARLES T. BLOOMER, citizens of the United States, residing at Newark, in the 5 county of Wayne and State of New York, have invented a new and useful Corner Construction for Boxes, of which the following is a specification.

The present invention appertains to a corner construction for paper, cardboard and similar boxes, such as are commonly employed for carrying or conveying suits of clothes, and the like, and the present invention is particularly an improvement over the 10 corner construction for boxes disclosed in the co-pending application of Charles E. Green, Serial No. 11,762, filed March 13, 1915.

The present invention has for its object 20 the provision of novel and improved means for attaching or fastening together the adjacent walls of a box, box cover or equivalent structure, whereby the walls will be held against inward as well as against outward movement, and will be locked against detachment and separation, the present invention eliminating the use of ordinary fasteners which readily tear loose so as to permit the box to break or burst open.

It is also the object of this invention, the 30 same as with the invention disclosed in the above mentioned application, to provide a corner construction for boxes of the nature indicated, which will be comparatively simple, non-encumbering and inexpensive in 35 construction, which will not require excessive or additional stock to be employed or which will lie within the outline of the blank box, and which will be convenient, efficient 40 and thoroughly practical in use.

With the foregoing and other objects in view which will appear as the description 45 proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

The invention is illustrated in its preferred embodiment in the accompanying drawing, wherein:—

Figure 1 is a perspective view of one corner of a box illustrating two adjacent walls of the box secured together by means of the

improved corner construction. Fig. 2 is a fragmentary plan view of one corner of the blank from which the box is folded. Fig. 3 is a view similar to Fig. 2 illustrating the 60 parts of the adjacent walls as being folded and secured, ready for the interlocking of the walls with each other. Fig. 4 is a sectional detail through the corner of the box, on the line 4—4 of Fig. 1. Fig. 5 is a perspective view of the corner of the box, with the adjacent walls unlocked or detached. 65

Since the present device is an improvement over the device disclosed in the application, *supra*, reference is made to the said 70 application for the general utility and features of the corner construction. It may be said, however, that with the corner construction disclosed in the said application, although the walls of the box are locked 75 against outward movement, the wall having the pocket is free to move inwardly, which in some cases would prove objectionable since it would enable the walls to become detached, although the corner construction disclosed in the said application would be thoroughly efficient in many cases and would be 80 efficient and desirable for certain uses of the box.

The present box is formed from a blank of 85 paper, cardboard, or similar flexible stock, as usual, and since the present invention resides in the corner construction, only one corner of the box is illustrated, although it will be evident that the present invention 90 may be employed for each corner of the box. The blank embodies the body 1 which forms the bottom of the box when the blank is folded, and the body 1 of the blank has portions which are folded upward to provide 95 the side walls of the body, only two of the portions or side walls 2 and 3 being illustrated.

In carrying out the invention, reference 100 being had particularly to Fig. 2 wherein the construction is illustrated in blank form, the end of the wall 3 adjacent the adjacent wall 2 is provided with a tapered or approximately triangular flap 4 projecting therefrom, the free end of the flap 4 being cut 105 off, as at 5, and there being a fold line 6 between the wall 3 and the base of the flap 4.

The adjacent end of the wall 2 has a flap 7 projecting therefrom adjacent the flap 4, the two flaps being separated by a slit or 110 cut extending to the corner of the body or bottom 1, between the walls 2 and 3 and

there is also a fold line 8 between the wall 2 and base of the flap 7. The flap 7 is provided with a portion 9, which is foldable back against the outer side of the body portion of the flap 7, upon the diagonal or oblique fold line 10 extending from the free end of the flap 4 to that side of the base of the flap 7 remote from the flap 4. That edge portion of the portion or supplemental flap 9 of the flap 7 which is remote from the flap 4, is provided with a recess or notch 11.

When the blank is cut or struck from the stock, the flaps 4 and 7 may be readily formed therein, and it will be noted that the flaps lie within the outline of the blank, in order that excessive or additional stock will not be required. This is of advantage, since the waste incident to ordinary corner fasteners is eliminated. The flaps 4 and 7 are then bent or folded to provide the interengagable portions or members carried by the adjacent ends of the adjacent walls 2 and 3; and to this end the flap 4 is folded back or reflexed against the inner side of the wall 3 parallel therewith, and a staple or other securing element 12 is engaged through the basal portion of the flap 4 and the wall 3 between the side edges of the said flaps. The staple or securing means 12 therefore holds the flap 4 in place adjacent the inner side of the wall 3 of the box with the flap 4 projecting inwardly or away from the respective end of the wall 3.

The portion 9 of the flap 7 is folded back against the outer side of the body portion of the flap 7, upon the fold line 10, the body portion of the flap 7 and the portion 9 being of triangular contour and coinciding when they are folded together, and a staple or securing element 13 is then driven or engaged through the body portion of the flap 7 and the portion 9 of the said flap adjacent the apices of the said portions. Thus, the portions of the flap 7 will be secured or held together, and will provide a triangular pocket 14 whose mouth is disposed adjacent the end of the wall 2 and which pocket opens outwardly and away from the wall 3 of the box. It will be noted that the body portion of the flap 7 provides the inner side of the pocket 14, while the portion 9 of the said flap provides the other side of the said pocket, the outer side of the pocket or portion 9 having a recess or notch 11 adjacent 55 and extending away from the mouth of the pocket.

The doubled portion 7-9 which is located at the inner side of the wall 3 projects angularly in one direction from the wall 2, and is provided with the pocket 14 opening in the opposite direction at the basal portion of the doubled portion, whereby the bent back flap 4 at the end of the wall 3, which is located at the inner side of said wall, by fitting in said pocket, will thereby hold said

walls against separation and outward movement, the flap 4 projecting in the same direction as the doubled portion.

Particular attention is directed to the fact that in the present device, the portion or side 70 5 of the pocket 14 is provided with a projection or extension 15 which enters in combination with or which co-operates with the other parts to accomplish new and useful results.

The parts are thus secured together by the staples or securing means 12 and 13 at the factory, and the box may still remain in blank form, in order that the blanks may be stacked or bundled as usual, and without requiring the boxes to be erected before it is necessary or desirable to use them.

With the parts secured together as illustrated in Fig. 3, and as above described, the side walls 2 and 3 of the box may be readily and effectively secured or locked together for holding the walls 2 and 3 together in a firm and efficient manner. To attach the side walls 2 and 3 together, they are folded upwardly at an angle to the bottom 1, and the parts are properly manipulated to insert the reflexed or bent back flap 4 into the pocket 14, whereby the pocket which is bent inwardly will snugly receive the flap or tongue 4 and rest against the inner side of the wall 3.

The flap 4 is engaged within the pocket 14 by swinging the wall 2 inward toward the bottom 1 after the wall 3 has been swung to erect position perpendicular with the bottom 1, and which will bring the pocket 14 to such a position adjacent or beyond the free portion of the flap 4, to allow the flap 4 to be readily received by the pocket 14 when the wall 2 is swung back to upright or erect position. The recess or notch 11 of the portion 9 will receive and accommodate the staple or securing element 12, while the cut away portion 5 of the flap 4 will prevent the flap 4 from interfering with the staple 13 at the apex of the pocket and in order that the members of the side walls may be properly and effectively interlocked.

The corner of the box, when the side walls are attached together, will be thoroughly substantial and will not be liable to break or burst open when outward pressure is exerted against the side walls of the box. Since the pocket 14 of the side wall 2 is engaged over the flap 4 of the wall 3 with the portion 9 projecting between the flap 4 and wall 3 beyond the staple 12, the wall 2 cannot swing outward, and since the flap 4 of the wall 3 is received in the pocket 14 of the wall 2, the wall 3 cannot swing outward, and as a consequence, the interengagement of the members of the walls 2 and 3 will efficiently hold the walls against separation, and the parts will not be liable to tear loose, as is frequently the case with the or-

dinary fasteners of clothing and similar boxes.

Especial attention is directed to the fact that when the box is erected, the pocket 14 being bent or swung inwardly, to the position illustrated in Fig. 5, will cause the projection or stop 15 to project downwardly or depend from the portion or side 9 of the pocket 14 when the wall 2 is in upright position, and as a result, the projection or stop 15 will rest upon the bottom or body 1 of the box. The projection or stop 15 is flexible or bendable, however, in order that it may be bent inwardly under the body portion 15 of the flap 7, to enable the wall 2 to be moved inwardly sufficiently, in order that the flap 4 and pocket 14 may be interengaged. When the flap 4 and pocket 14 are interengaged and the walls moved to proper 20 position perpendicular with the body or bottom 1, the projection or stop 15 will spring back to normal position against the wall 3 and will thereby hold the pocket 14 in position, and will prevent the pocket 14 25 and the wall 2 from swinging inwardly, so as to prevent the pocket from disengaging the flap 4. As a result of the provision of the projection or stop 15, the efficiency and utility of the corner construction is enhanced considerably, and the adjacent walls 2 and 3 cannot be accidentally detached and can only be detached by manually swinging the projection or stop 15 inwardly so as to allow the pocket 14 to be moved inwardly 30 out of engagement from the flap 4.

From the foregoing, taken in connection with the drawing, the many advantages and capabilities of the present invention will suggest themselves to those versed in the art and further comment is deemed unnecessary.

Having thus described the invention, what is claimed as new is:—

1. In a device of the character described, 40 a body having adjacent walls, one wall hav-

ing a doubled portion at the inner side of the other wall and projecting angularly in one direction from the first mentioned wall, and said portion having a pocket opening in the opposite direction, the second mentioned wall having a portion at its inner side projecting in the same direction as the first mentioned portion and adapted to fit in said pocket, whereby the walls are thereby held against separation and outward movement, 50 the first mentioned portion having an extension seating against the body for holding said portions in engagement with one another.

2. In a device of the character described, 60 a body having adjacent walls, one wall having a doubled flap at one end and at the inner side of the other wall and projecting angularly in one direction from the first mentioned wall, said doubled flap providing a 65 pocket opening in the opposite direction, the second mentioned wall having a portion bent back from one end and located at the inner side thereof, said portion projecting in the same direction as the doubled flap 70 and being adapted to fit in said pocket, whereby the walls are thereby held against separation and outward movement, the free portion of said flap having an extension seating against the body for preventing the inward movement of the doubled flap.

In testimony that we claim the foregoing as our own, we have hereto affixed our signatures in the presence of two witnesses.
